UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 15,028, dated May 27, 1884.

Application filed March 27, 1884. Term of patent 34 years.

To all whom it may concern:

Be it known that I, SARAH JANE SHIELS, of the city, county, and State of New York, have invented and produced a new and original 5 Design for a Pattern of a Miss's Costume, (numbered 9,177;) and I do hereby declare that the engraved prints accompanying this specification convey to any one accustomed to using paper patterns a clear understanding of how a 10 garment made up by the pattern will appear.

The design shows a walking-skirt and an overdress. The overdress displays a closely-fitted basque-like left front, a closely-fitted polonaise right front having the appearance 15 of overlapping the left front, under buttons, in a curve from the throat to the left hip, displaying draping-plaits in its back edges and

falling in a deep point at the left side of the center, a closely-fitted polonaise-back exhibiting under-folded plaits at the lower ends of 20 its middle three seams, draping-plaits in its left front edge and loopings at its center and front edges, coat-sleeves, and a standing collar.

What I claim as my invention, and desire to secure by Letters Patent, is—

The design for a miss's costume, as shown in 25 the engraved prints accompanying this specification.

SARAH JANE SHIELS.
